(74) *Attorney, Agent, or Firm* — Gearhart Law, LLC

(57) **CLAIM**

The ornamental design for a distillation head, as shown and described.

DESCRIPTION

FIG. 1 is a perspective view of a first embodiment of the distillation head.

FIG. 2 is a front view of FIG. 1.

FIG. 3 is a back view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1.

FIG. 8 is a perspective view of a second embodiment of the distillation head.

FIG. 9 is a front view of FIG. 8.

FIG. 10 is a back view of FIG. 8.

FIG. 11 is a left side view of FIG. 8.

FIG. 12 is a right side view of FIG. 8.

FIG. 13 is a top view of FIG. 8; and,

FIG. 14 is a bottom view of FIG. 8.

The dashed lines shown in the drawings illustrate internal structures visible via the transparency of the distillation head, the dashed lines as indicated form no part of the claimed design.

1 Claim, 10 Drawing Sheets
